Attorney

UNITED STATES PATENT OFFICE.

CHARLES WEEKS, OF PALO ALTO, CALIFORNIA.

EGG-TURNING TRAY.

1,356,949.

Specification of Letters Patent. Patented Oct. 26, 1920.

Application filed March 3, 1919. Serial No. 280,375.

To all whom it may concern:

Be it known that I, CHARLES WEEKS, a citizen of the United States, residing at Palo Alto, in the county of Santa Clara and State 5 of California, have invented certain new and useful Improvements in Egg-Turning Trays, of which the following is a specification.

This invention is an egg turner for incubators.

10 The invention is illustrated in the accompanying drawing which forms a part of this specification and the appended claims.

Referring to the drawing:

Figure 1 is a plan view of the invention. 15 Fig. 2 is a longitudinal section of the invention taken on line 2—2 of Fig. 1.

Fig. 3 is a cross section of the invention taken on line 3—3 of Fig. 1.

In the drawing, 1 indicates a frame and 20 a plurality of rollers extending transversely of the frame between the side rails 3 thereof, and journaled in metal bearing plates 4, nailed to the inside of said side rails, and in said side rails, said plates and side rails being drilled to receive the roller journals 5 which are driven in the ends of said rollers.

The ends of plates 4 may be bent at their ends and nailed to the inside of the end rails 6 of the frame 1. The rollers 2 are 30 spaced at a suitable distance apart to support the eggs which rest upon and between them. The inner upper edges of the side rails 3 are beveled so that the end eggs may extend partly over said rails, as shown in Fig. 3, 35 thus providing additional room for the support of a maximum number of eggs in the frame. Side flanges 7 secured to the outside of the side rails 3 at the upper edge thereof, are adapted to rest and slide upon strips 8 40 secured to the inside of the incubator 10, so that the frame may slide into and out of the incubator like a drawer.

A cord 15 is wound successively around the rollers 5 and extended downwardly from 45 the end rollers under the other rollers. By

grasping the lower reach of the cord and pulling it the rollers are rotated and the eggs resting upon and between them are turned uniformly and completely.

The device is simple in construction and 50 operation and may be manufactured cheaply.

Having described my invention, I claim:

1. An egg turning tray comprising a frame including side and end rails, bearing plates secured along the inner face of the 55 side rails and having their ends extended along the end rails and secured thereto, said plates and side rails having a longitudinal series of journal openings therein, rollers extending transversely over the frame and 60 having spindles at their ends rotatably received in said openings, the inner upper edges of the side rails of the frame being beveled from their upper surface to a point at least coincident with the surface of the 65 rollers, thereby increasing the egg containing capacity of the tray.

2. An egg turning tray comprising a frame including side and end rails, bearing plates secured along the inner face of the 70 side rails and having their ends extended along the end rails and secured thereto, said plates and side rails having a longitudinal series of journal openings therein, rollers extending transversely over the frame and 75 having spindles at their ends rotatably received in said openings, the inner upper edges of the side rails of the frame being beveled from their upper surface to a point at least coincident with the surface of the 80 rollers, thereby increasing the egg containing capacity of the tray, and an endless cord having one reach thereof wound successively around said rollers and having the other reach extending downwardly from the end 85 rollers and lying under the other rollers providing a pull-cord.

In testimony whereof I affix my signature.

CHARLES WEEKS.
